FIG. 4.

FIG. 3.

INVENTOR
HARRY F. GEIST

BY

Harry F. Geist
ATTORNEY

UNITED STATES PATENT OFFICE.

HARRY FOREST GEIST, OF AURORA, ILLINOIS.

MAGNETO.

Application filed May 6, 1921. Serial No. 467,494.

To all whom it may concern:

Be it known that I, HARRY F. GEIST, a citizen of the United States, and resident of Aurora, in the county of Kane and the State of Illinois, have invented new and useful Improvements in Magnetos, of which the following is a description, reference being made to the accompanying drawings, which are a part of the specification.

10 The invention relates to magnetos for ignition purposes.

The invention is more particularly designed to provide a magneto having stationary coils in which by the arrangement of 15 parts a machine of simple construction and efficient operation is obtained.

15 The invention is further designed to provide a machine in which the more vital parts are easily accessible and removable from 20 the body of the machine without disturbing the timed setting of the magneto with the engine it serves.

25 The invention is further designed to reduce the cost of manufacture through such an arrangement of its parts that iron may be largely used in its construction.

30 The invention further consists in the several features hereinafter set forth and more particularly defined by claims at the conclusion hereof. In the drawings—

Fig. 1 is an end elevation of a machine embodying my invention.

Fig. 2 is a side elevation of the machine.

35 Fig. 3 is a vertical section on line B—B of Fig. 2, and

Fig. 4 is a vertical section on line A—A of Fig. 1.

Similar numerals refer to similar parts throughout the several views.

40 For convenience in explanation, the mechanical construction of the machine will be described first together with its operation thereafter.

The frame of the machine consists of a 45 cast iron base piece 10 and an upper shell casting 11 also of cast iron, magnetically separated by non-magnetic parts 12 forming an integral structure by any suitable means known to the art. This frame has a tunnel or bore adapted to receive an inductor or 50 rotor as hereinafter described.

A very satisfactory method of constructing this frame would be to form parts 10 and 11 in one iron casting joined in such a way by tie sections that the boring operation would magnetically separate them. The

non-magnetic separating metal could then be cast in place with inexpensive means, before boring.

Base casting 10 is provided with suitable means such as tapped holes for securing the machine as a whole to the engine served and also presents an area to the bore of the machine for magnetic coaction with the rotor as hereinafter set forth. Means are also 65 provided for securing magnets to said base casting 10.

The shell casting 11 is provided with a set of vertical slides 13 formed integral with it on each side of the casting. These slides are 70 located midway between the ends of the machine on the inside of the shell. Slots 14 are also provided in the shell casting between the slides on each side of the machine.

An E-shaped pole piece 15 comprising a 75 plurality of soft iron laminae clamped together to form a unitary structure by means of rivets 16 is adapted to fit with slight pressure into the double ways formed by slides 13 and by slots 14, being located forward or 80 backward in the machine by said slides 13 and up and down by shoulders which rest upon the bottoms of slots 14.

This E shaped pole piece may be clamped in position after insertion by means of a 85 clamp or set screws or other well known means not shown. A principal feature of this construction is that the pole piece 15 is removable from the machine frame and that it presents also a plurality of prongs 90 for engagement with said rotor by terminating at the tunnel of the frame.

A form wound coil 17 is insulated and mounted upon the middle prong of the pole piece 15, being held in place by varnishes 95 and a fibre plate 18 notching between the middle prong and the outside prongs of the pole piece 15. The shell casting 11 provides ample space for the reception of the pole piece 15 and its coil 17.

One terminal of the coil 19 is grounded to the frame by means of a screw 20. The other terminal 21 is secured to a small brass terminal block 22 that is moulded in place in an insulator block 24 that straddles the 105 pole piece 15 and may be secured thereto as a part of a coil structure.

A lead 25 which attaches to the igniter of the engine (not shown) is secured to the insulated block 22 by a screw 26 being protected and insulated from the frame by a bushing 27 of suitable insulating material.

The machine is further provided with a top cover 28 which may be made of iron. This top cover is secured to the frame of the machine by screws 29.

5 The rotor or inductor consists of a plurality of laminæ 30 having a plurality of radially projecting prongs. These laminæ are clamped together forming a rotor body by means of rivets 31 and are pressed upon a 10 shaft 32 in a manner well known to the art. The rotor is further provided with a pair of spacer collars 33 pressed upon the shaft 32, for centrally locating the rotor body.

15 The rotor is further journaled at each end in bronze or other suitable bearings 34 which are pressed into bearing plates 35. Bearing plates 35 are of non-magnetic material for the construction shown, but for a modification of the frame shell casting 11 20 they may be made of iron. These bearing plates 35 are dowelled to the tunnel of the machine and secured thereto by means of screws 36.

25 Shim washers 37 are provided between parts 33 and 34 at each end of the shaft to take care of end play. The bearings are oiled through parts 38 or other suitable means.

30 A pair of magnets 39, of the flat arched type are secured to the sides of the machine by screws 40, like poles contacting with the base casting and other like poles contacting with the iron shell casting 11 and with parts of the upper removable pole piece 15 which 35 project through slots 14 of casting 11, without interfering with the removability of said part 15 from the machine.

40 From the construction of the machine, it is evident that the base casting 10 represents one pole piece of the magnetic field by contact with the magnets 39, and that part 15 represents the opposite pole piece by contact with the shell casting 11 which is of iron and which contacts with the magnets 39 and 45 also by direct contact of 15 with 39 as described. It is also evident that the construction anticipates either the magnetic contact between parts 15 and 39 alone or between parts 11 and 39 alone, in which 50 latter case 15 will be magnetically polarized by 39 through the medium of portion 11. Both the pole pieces 15 and 10 terminate with certain areas at the tunnel of the machine.

55 The rotor 30 represents a plurality of radially projecting prongs which coact both with the pole piece 10 and the pole piece 15 to generate energy in the windings 17 in a manner well known to the art.

60 It is well known that, during the process of energy generation in the windings 17, produced by flux shifted from the central polar projection to the outside by-pass polar projections of part 15 or vice versa, reactive 65 flux forces are established in the coil and

take paths through the polar projections of part 15. Since the iron shell casting magnetically connects the two outside by-pass polar projections, it also will be subject to the reactive flux forces,—increasing as it 70 does the permeability of the paths and hence increasing the inductance per turn of the coil. Shell casting 11, therefore forms a magnetic as well as a mechanical housing for the windings. 75

While this rotor may perform such generation by continuous rotation, this type of machine finds its most advantageous use in such systems as employ springs for the actuation of the rotor. 80

While the machine shown herewith represents a low tension magneto, it can by employing sufficient number of turns to the coil 17 and sufficient speed of motion to the rotor be made to deliver a jump spark. Or 85 by providing the machine with a primary and a secondary winding, together with a suitable interrupter for the primary circuit and condenser for the interrupter, a machine of the conventional high tension type may 90 be constructed embodying the principal features of this invention.

I am aware that the specific construction details as herein described are subject to modification and change and I therefore desire it understood that such changes and modifications as come within the scope of the appended claims are within the spirit of my invention. 95

What I claim as my invention is— 100

1. In an inductor type magneto, the combination of a field magnet provided with an iron base pole piece of one magnetic polarity and an iron shell portion of opposite polarity, and a removable soft iron pole 105 piece including a plurality of polar projections and carrying windings, said soft iron pole piece being adapted to be supported by and of the same magnetic polarity as said shell portion, said shell portion having walls substantially parallel to sides of said windings formed by convolutions of equal periphery and forming a magnetic housing for said windings, and a rotor adapted to be actuated between said pole pieces for energy 110 generation in said windings. 115

2. In an inductor type magneto, the combination of a field structure comprising a field magnet, a frame and a coil structure, 120 said frame including a magnetic pole piece of one polarity and an iron shell casting of opposite polarity, said coil structure including a soft iron pole piece having spaced apart polar projections and carrying windings, said iron shell casting forming a magnetic housing for said windings and adapted to support said coil structure, and a rotor 125 adapted to be actuated between said pole pieces for energy generation in said windings. 130

3. In an inductor type magneto, the combination of a field structure comprising a field magnet, a frame and a removable coil structure, said frame including a polar portion terminating with an area at a bore and supporting one pole of said magnet and a shell casting diametrically opposite thereto having a tunnel opening at right angles to said bore and supporting the other pole of said magnet, said removable coil structure comprising a soft iron pole piece having spaced polar projections terminating at said bore and carrying windings and adapted to be supported in the tunnel opening of said shell casting and in contact with said magnet, and a rotor adapted to be actuated in said bore between said pole pieces for energy generation in said windings.
4. In an inductor type magneto, the combination of a field magnet provided with a polar portion of one magnetic polarity presenting an area at a bore and an iron shell casting of opposite polarity diametrically opposite thereto having a tunnel opening at right angles to said bore, and a removable coil structure comprising a soft iron pole piece having spaced polar projections terminating at said bore and carrying windings, said removable coil structure being adapted to be supported in said tunnel opening and of the same magnetic polarity as said iron shell casting, and a rotor adapted to be actuated in said bore between said pole pieces to generate energy in said windings.
5. In an inductor type magneto, the combination of a field magnet provided with an iron base pole piece of one polarity and a laminated iron pole piece of opposite polarity, said laminated iron pole piece including a plurality of spaced apart projections and carrying windings and magnetic means housing said windings and a rotor adapted to actuate between said pole pieces for energy generation in said windings.
6. In an inductor type magneto, the combination of a field structure comprising a field magnet, a frame, a coil structure and an iron top cover, said frame including a magnetic pole piece of one polarity and an iron shell casting of opposite polarity, said coil structure including a soft iron pole piece having spaced polar projections and carrying windings and adapted to be supported by and of the same magnetic polarity as said shell casting, said shell casting and said iron top cover forming a magnetic housing for said coil structure, and a rotor adapted to be actuated between said pole pieces for energy generation.
7. In a magneto frame, an iron casting comprising a polar portion having an area terminating at a bore, a shell portion having a tunnel opening at right angles to said bore, and tie sections uniting said polar portion and said shell portion in a unitary structure, said tie sections providing spaces between said polar portion and said shell portion for casting in non-magnetic metal that will mechanically bind and magnetically space said polar portion and said shell portion when said tie sections are machined away during the process of manufacture.
8. In a coil structure for inductor generators, a soft iron pole piece of substantially E shaped laminate and a coil mounted thereon, said pole piece comprising a central polar projection adapted to direct magnetic flux through said coil and two by-pass polar projections adapted to direct magnetic flux outside of said coil, said by-pass polar projections being otherwise magnetically connected by iron castings forming a magnetic housing for the sides of said coils substantially as described.
9. In a coil structure for inductor type generators, a soft iron pole piece comprising three spaced apart polar projections integral with a connecting bar and a coil, said coil being mounted upon the central polar projection of said pole piece, said other polar projections and said connecting bar being otherwise magnetically connected by iron castings forming a magnetic housing for the sides of said coils substantially as described.
10. In a coil structure for inductor generators, a soft iron pole piece comprising a plurality of spaced apart polar projections integral with a connecting bar and coils, said coils being mounted upon certain polar projections of said pole piece and certain other polar projections and said connecting bar being magnetically connected by iron shell parts forming magnetic housings for the coils, substantially as described.
11. In an inductor type magneto, the combination of a field structure comprising a field magnet, a frame and a coil structure, said frame including a magnetic pole piece of one polarity terminating at a bore and an iron shell casting of opposite polarity, said coil structure including a soft iron pole piece having spaced apart projections terminating at said bore and carrying windings, said iron shell forming a magnetic housing for said windings and having means for positively locating said coil structure with respect to said bore, and a rotor adapted to actuate in said bore between said pole pieces for energy generation in said windings.

HARRY FOREST GEIST.
